UNITED STATES PATENT OFFICE.

ANDREW McGAFFEY, OF BATTLE CREEK, MICHIGAN.

FOOT-GUARD FOR RAILWAYS.

SPECIFICATION forming part of Letters Patent No. 309,555, dated December 23, 1884.

Application filed July 14, 1884. (No model.)

To all whom it may concern:

Be it known that I, ANDREW McGAFFEY, a citizen of the United States, residing at Battle Creek, in the county of Calhoun and State of Michigan, have invented certain new and useful Improvements in Frogs and Switch-Filling for the Protection of Life of Brakemen and Others on Railroads; and I do hereby declare that the following is a full, clear, and exact description of the same, reference being had to the annexed drawings, making a part of this specification, and to the letters and figures of reference marked thereon.

Figure 1 of the drawings is a perspective view of my invention; Fig. 2, a cross-section thereof; Fig. 3, a detail view of the filling, consisting of the plate and blocks; and Fig. 4, a detail view of one of the blocks.

The object of the present invention is to provide a simple and effective means for the protection of life of brakemen and others on railroads; and it consists in a filling for frogs and switches, as will be hereinafter described and claimed.

In the accompanying drawings, A represents the rails of a switch or frog supported upon the cross-ties B, and between these rails I secure the filling, which consists of the surface-plate C, preferably of wrought-iron, and supported at its ends by cast-iron blocks D, and connected thereto by suitable spikes, a. said spikes passing through the plate and

blocks and into the cross-ties. The surface-plate C is concave, so that it will not come flush with the tread of the rails, and at its sides has downwardly-bent flanges b, extending the entire length thereof, to come under the tread of the rails, and form a perfect joint. The blocks D upon their upper sides are concave, as shown at c, to correspond with the convex under surface of the plate C, and have beveled ends d and e, so as to enter between the tread and base of the rails, the beveled ends d corresponding in form to the flanges b, to provide a support therefor.

Having now fully described my invention, what I claim as new, and desire to secure by Letters Patent, is—

A filling for frogs and switches, consisting of a concavo-convex metal plate placed between the rails, and having at its sides downwardly-bent flanges and concave blocks for supporting the ends of the plate formed with beveled ends to extend under the tread of the rails, substantially as and for the purpose set forth.

In testimony that I claim the above I have hereunto subscribed my name in the presence of two witnesses.

ANDREW McGAFFEY.
